BINDER

Walter Easter Haskin, New York, N. Y., assignor to Pressed and Welded Steel Products Company, Inc., Long Island City, N. Y., a corporation of New York

Application November 21, 1951, Serial No. 257,569

3 Claims. (Cl. 129—1)

This invention relates to binders and more particularly to loose-leaf post binders for perforated paper sheets, pamphlets and the like which may be frequently referred to.

An object of the invention is to provide a binder adapted to hold a multiple of perforated paper sheets, pamphlets and the like for pivotal mounting in connection with my improved book stand, an application for patent on which was filed July 21, 1926, Serial No. 124,011, which matured into a patent issued October 9, 1928, numbered 1,687,443. The book stand embodies the following three elements: a casing, a binder partially concealed in the casing and means pivotally connecting the binder intermediate the ends thereof to said casing for supporting and permitting said binder to swing around said pivot outside of said casing in position for use.

A further object of this invention is to provide a binder of durable construction primarily adapted to withstand rough usage at the hands of the public and, also, in the field to afford means for ready replacement of parts damaged in use.

This invention also relates to my application for a patent on a binder filed April 23, 1929, Serial No. 357,551, which matured into a patent issued June 24, 1930, numbered 1,767,978, and to my copending application for a patent on a binder filed November 5, 1948, Serial No. 58,425 which matured into United States Letters Patent No. 2,617,422 dated November 11, 1952. It is distinguished from the latter application in that it concerns itself with the handling of perforated loose paper sheets or pamphlets as contrasted with bound books such as telephone directories and the like. It includes improved construction, improved means for removably holding loose paper sheets, pamphlets and the like and improved means for locking the parts in operative connection.

This invention further relates to my copending application for a patent on a binder filed February 23, 1949, Serial No. 77,959, now abandoned. Compared therewith it includes improved construction by eliminating the retaining studs and latching member and employing in their stead a part of the existing book coupling means of the first above mentioned copending application, Serial No. 58,425, for locking the post-carrying unit in operative engagement.

With these and other objects in view, the invention consists in certain novel features of construction and combination and arrangement of parts, which will be more fully hereinafter described and pointed out in the claims.

In the accompanying drawings—

Fig. 1 is a plan view of the binder in open position;

Fig. 2 is a longitudinal section on the line 2—2 of Fig. 1;

Fig. 3 is a transverse section on the line 3—3 of Fig. 1;

Fig. 4 is a plan view of the respective post-carrying plates;

Fig. 5 is a longitudinal section on the line 5—5 of Fig. 4;

Fig. 6 is a plan view of a modification of the structure shown in Fig. 4;

2

Fig. 7 is a longitudinal view on the line 7—7 of Fig. 6.

Referring to the accompanying drawings by numerals, the binder is provided with a rigid backbone member of any desired material as, for example, a metal channel-shaped section, preferably of polished stainless steel, comprising a flat back plate 1 formed with perpendicular side walls 2 as illustrated in Fig. 3. As shown in Fig. 2 the back plate is formed at one end with a perpendicular end wall 3 extending beyond the side walls and which is provided with an offset 4 and an extension which is formed at its free end to provide a cylinder 5. As illustrated in Fig. 1, the cylinder is provided with a series of slots 6. Positioned for reciprocal operation in the cylinder 5 and guided by the offset 4 is a U-shaped wire 7 which is formed with an offset extension at the free extremity of one leg and which is prevented from complete removal from the cylinder by contact with a retaining lip or detent formed in the end wall 3. The back plate at the opposite end is folded back on itself to form a projecting ledge 8 merging into a perpendicular end wall 3' extending beyond the side walls and which is likewise provided with an offset 4' and a cylinder 5' at its free end, as shown in Fig. 2. This cylinder is likewise provided with a series of corresponding slots 6' and a reciprocally operating U-shaped wire 7' which is retained in the same manner as above described.

Positioned in the side walls 2 of the back at any point intermediate the ends thereof are extruded apertures 9. The side walls are provided at their outer free edges with hinge knuckles 10 to which are attached the complementary hinge leaves 11 by means of the loose hinge pins 12. Attached to the hinge leaves 11 are the side covers 13 which may be made of any suitable material such as "Bakelite," "Masonite," fiber or metal.

Nested in the back member 1 is an inner channel-shaped member 14 comprising a platform plate 15 formed with perpendicular side walls 16 in which are positioned apertures 17 intermediate the ends and aligned with the extruded apertures 9 of the back member as shown in Fig. 3. The side walls are provided at their outer free edges with inwardly projecting stiffening flanges 18 as shown in Fig. 2. The platform plate is formed at each end into a perpendicular flange 19 and 19' merging into outwardly projecting extensions 20 and 20' of different lengths. The shorter flange extension 20 engages the angular projection 21 positioned on the end wall 3 of the back member. The longer flange extension 20' is positioned to enter the space created by forming the projecting ledges 8 of the back member.

In the assemblage of parts the inner channel member 14 is positioned inside the back member to form a hollow tubular structure. In this operation the longer flange extension 20' is first positioned to enter the ledge 8 and then projected therein to the limit of its movement. Thereupon the shorter flange extension 20 is positioned to slide under the angular projection 21 of the end wall 3 and the inner channel unit is then moved in the opposite direction longitudinally of the back until the shorter flange extension is securely seated under the angular projection 21 to removably attach the inner channel member to the back member firmly at both ends. At the same time the respective apertures 17 of the inner channel and 9 of the back member are brought into alignment. A rod 22 may then be passed through the respective apertures so that the back and inner channel members of the binder are securely locked against accidental movement in any direction.

The binder is adapted to pivot on the rod and is especially designed for use with my improved book stand. The projecting ledge 8 provides a finger grip to facilitate turning the binder on its pivot.

For the purpose of handling perforated loose leaves

or pamphlets in the binder, there is removably mounted over the platform plate 15 an auxiliary post-carrying unit 23 comprising two reciprocatingly operating angular metal plates 24 and 24' preferably of polished stainless steel. As shown in Figs. 4 and 5 the base plate 24 is provided at each end with a folded back return 26 and 26' forming an outwardly projecting guideway or slide to receive and retain the complementary plate 24' in its reciprocating action, and to prevent longitudinal movement of the two plates with respect to each other when the post-carrying unit is uncoupled from the binder proper.

Formed along one side of the base plate 24 is a perpendicular flange 27 on which is mounted a series of not less than two metal posts 25. The complementary plate 24' is likewise provided with a perpendicular side flange 27' having not less than two posts 25' mounted in staggered arrangement with respect to the opposite posts 25 of the base plate 24. The perpendicular side flanges of the respective plates are formed at each end with inwardly projecting right angle extensions 28 and 28' merging into right angled secondary longitudinal extensions 29 and 29' with notches or perforations 30 therein adapted to be positioned in the slots 6 and 6' in the cylinders 5 and 5' of the back plate 1 and retained therein by the respective U-shaped wires 7 and 7'.

In operation, the loose leaves 31 Figure 2 or other material to be entered in the binder are prepared with perforations along their inner margins to correspond with the spacing of the respective sets of binding posts. For example, the drawings show a total of four posts, one pair positioned on each of the plates 24 and 24' in staggered arrangement and the material would therefore be provided with four similarly spaced perforations to enable all four posts to enter therein simultaneously. The perforated material is then mounted on one set of two posts 25 attached to the base plate 24.

The complementary plate 24' is then positioned on the under side of and with its ends entered in the guideways 26 and 26' of the base plate 24. The two plates are then brought together to a fully closed telescoping arrangement with the remaining two posts 25' projected into the corresponding vacant perforations. The post-carrying unit with its contents is thereupon coupled to the above described binder proper in the following manner:

The post-carrying unit 23 is positioned upon the platform plate 15 and moved longitudinally of the platform plate so that the secondary notched extensions 29' at one end will be projected into the slots 6' of the cylinder 5' so that the wire 7' will enter the notches 30. Thereupon the wire 7 at the opposite end of the platform plate is withdrawn from the cylinder 5 to the limit of its movement permitting the opposite notched extensions 29 to be entered in the cylinder slots 6. The wire 7 is then returned to its normally closed position whereby the post-carrying unit with its contents is securely coupled to the binder proper in operative engagement. To remove the post-carrying unit and its contents from the binder proper the operation is the reverse of the coupling manner described.

It is to be noted that in the post-carrying unit above described the respective plates are each provided with a minimum of two solid binding posts positioned in staggered arrangement. In the case of perforated loose leaves, if it is desired to remove or insert new sheets at any given intermediate position in an alphabetical or numerical arrangement the post-carrying unit is first uncoupled from the binder proper and the contents separated at the given point. Thereupon the plates are separated with one portion of the contents being carried by the two posts of the base plate and the balance of the contents being carried by the two posts of the complementary plate so that the insertion of new material may be readily made at the point of separation, whereupon the plates are reassembled and the unit again coupled to the binder proper.

The device is thus provided with means to readily couple the post-carrying unit to the binder proper and to enable the loose leaves or other material contained therein to be rotated about a pivot without disengagement or damage thereto, and to readily uncouple the said unit for the purpose of alterations or additions to its contents.

A modification of the structure of the post-carrying unit is illustrated in Figures 6 and 7 of the drawings wherein the binding posts comprise two members, one of which 10 consists of a solid metal post 32 adapted to enter a complementary tubular post or sleeve 33 in telescopic arrangement so that the solid post may be reciprocatingly operated therein. A series of not less than two solid metal posts 32 are mounted as shown on the perpendicular flange of an annular member 34 and a series of tubular metal posts 33 are mounted in exactly opposite arrangement on the complementary angular member 34'. The perpendicular flanges of the respective angular members are formed at each end with inwardly projecting extensions 20 35 merging into secondary extensions 36 having notches or perforations 37 for coupling the post-carrying unit to the binder proper exactly in the manner previously described.

As shown in Fig. 7, the base or horizontal flanges of 25 the respective angular members 34 and 34' are formed at each end with inwardly projecting extensions 38 for the purpose of reinforcing the extensions 35 of the perpendicular flanges to which the former are attached.

In the modified structure the angular post-carrying 30 members 34 and 34' by reason of the telescoping feature of the binding posts mounted thereon are prevented from longitudinal movement with respect to each other when the post-carrying unit is uncoupled from the binder proper and the necessity for the telescoping feature of the plates 35 themselves in the structure previously described is thus eliminated and the number of telescoping binding posts and sheet perforations may be reduced to a minimum of two as compared to a minimum of four solid posts and sheet perforations in the previously described structure.

Inasmuch as this binder is especially adapted for public use in the display of data in loose-leaf form which is frequently referred to, it has been so designed as to permit of ready replacement of damaged parts in the field. It is to be noted that the major elements of the binder proper are locked together in operative engagement by a removable rod 22. Upon removal of this rod these elements may be readily disassembled by hand for servicing in the field. The auxiliary loose-leaf binding element may likewise be readily disengage from the device for repair, upkeep or replacement.

While I have illustrated and described what I believe to be the preferred embodiment of my invention, it is obvious that changes may be made in the general form and arrangement of the parts without departing from the spirit of the invention; hence I consider myself at liberty to make such changes and alterations as fairly fall within the scope of the claims.

I claim:

1. In a loose leaf binder the combination of a back plate formed with perpendicular end walls terminating in slotted cylindrical coupling means adapted to receive a loose leaf element, and side walls having side covers hingedly attached thereto and aligned apertures therein intermediate the ends, an inner platform channel plate nested inside the back plate and having similarly aligned side wall apertures, a removable rod passing through the respective apertures to lock the said plates in operative engagement to form a rigid rectangular hollow structure with the rod also acting as an integral support for the binder and a loose leaf binding post element having binding parts positioned on said platform plate and secured at each end by the said coupling means of the back plate, a plurality of marginally perforated loose leaves transfix by the said binding posts whereby when 60 65 70 75 the binder is supported by the said rod the loose leaves

are securely coupled thereto for movement without dislodgment.

2. A device in accordance with claim 1 in which the binding post carrying element comprises a pair of reciprocatingly operative flat metal base plates each having a perpendicular flange along one side extending beyond the base plate and terminating at each end in an angular extension having a notch therein, the said notched extensions being spaced apart and adapted to enter the said slots in the end cylinders of the back plate and secured therein by movable internal pins, the said side flanges each having a minimum of two inwardly projecting binding posts mounted therein in alignment with and spaced apart in staggered arrangement relative to the opposite posts and having a plurality of loose leaves impaled thereon whereby when the binding post element is mounted on the said platform plate with the notched extensions locked in the cylinder slots the respective plates are prevented from lateral movement away from each other and the loose leaves are securely coupled to the binder.

3. A device in accordance with claim 2 in which one of the pair of reciprocatingly operative base plates of the binding post carrying element is formed at both ends

with a bent back flange adapted to engage the flat ends of the complementary plate and to form a guide for the reciprocal telescoping manipulation of the respective plates toward and away from each other, so that when the post carrying element is detached from the binder the plates are enabled to be freely moved laterally but are restricted in their relative longitudinal movement whereby the separation, alteration and reassembly of the leaves is greatly facilitated.
